RECESS BRACKET FOR NIGHT LIGHT

Bernard Berger, Chicago, Ill., assignor to National Steel Cabinet Company, Chicago, Ill., a corporation of Illinois

Application June 5, 1952, Serial No. 20,054

Term of patent 14 years

(Cl. D48—4)

Fig. 1.

Fig. 2.

Fig. 3.

Fig. 1 is a front elevational view of a recess bracket for night light embodying my new design.

Fig. 2 is a side elevational view thereof.

Fig. 3 is a top plan view thereof.

The dominant portions of the design are shown in full lines.

I claim:

The ornamental design for a recess bracket for night light, substantially as shown and described.
